UNITED STATES PATENT OFFICE.

ZOUAVE S. RANDLEMAN AND CHARLES L. RANDLEMAN, OF DES MOINES, IOWA.

AUTOMATIC SAFETY-ALARM FOR RAILROAD-CROSSINGS.

1,315,685.

Specification of Letters Patent.

Patented Sept. 9, 1919.

Application filed October 22, 1918. Serial No. 259,270.

To all whom it may concern:

Be it known that we, ZOUAVE S. RANDLEMAN and CHARLES L. RANDLEMAN, citizens of the United States, and residents of Des Moines, in the county of Polk and State of Iowa, have invented a certain new and useful Automatic Safety-Alarm for Railroad-Crossings, of which the following is a specification.

10 The object of our invention is to provide an automatic safety alarm for railroad crossings which will be actuated by an approaching train for sounding an alarm at the crossing.

15 A further object is to provide such a device of extremely simple, durable and inexpensive construction which will be intermittently sounded by means actuated by the passing wheels of the train.

20 With these and other objects in view our invention consists in the construction, arrangement and combination of the various parts of the device, whereby the objects contemplated are attained, as hereinafter more fully set forth, pointed out in our claims, and illustrated in the accompanying drawings, in which:

Figure 1 shows a top or plan view of the actuating mechanism.

30 Fig. 2 shows a top or plan view of the alarm device with the casing thereon.

Fig. 3 shows a vertical, sectional view through the casing, and one end of the shaft on which the actuating trigger device is

35 mounted.

Fig. 4 shows a top or plan view of the alarm device with the casing removed, part of the device being shown in horizontal section.

40 Fig. 5 shows a perspective view of the portion of the rail illustrating the trigger device adjacent thereto; and

Fig. 6 shows a perspective view of the sounding device.

45 In the accompanying drawings we have used the reference numeral 10 to indicate generally the base of a rail having the upper portions 26. Spaced from the track is an upright 11.

50 Secured to the upright 11 are parallel laterally extending arms 12. Supported between the arms 12 on a short shaft or the like 12^a and spaced from the arms 12 by means of spacer sleeves 13, is a disk 14 of

55 any resounding metal, such as bell metal

or steel or the like. Supported on each arm 12 is a cylinder 14^a.

Each arm 12 is provided with an opening 12^b, as illustrated by dotted lines in Fig. 4, which registers with the end of the cylinder 14^a adjacent to said arm, and through which the alarm member 14 may be struck.

At the outer end of each cylinder 14^a is a closure member 15, which has a hole through which is extended a stem or sliding rod 17, 65 having on one end a head 16. Between the head 16 and the partition 15 is a coil spring 18. Between the head 16 and the arm 12 on which the cylinder 14^a is mounted, is a steel ball 19.

Secured to the rod 17 is a flexible member 19^a which may be a chain or any suitable cable device.

The alarm device may have two cylinders 14^a, and connected parts, as illustrated in 75 Fig. 2. In Fig. 4 we have shown only one of said cylinders, insomuch as the cylinders are alike where two are employed.

The chain 19^a extends along the track and may be supported on uprights and extends 80 along the track to the actuating mechanism hereinafter described.

The chain 19^a may be included in the conduit or supported on uprights or in any suitable way.

I provide a cover casing 28 for the alarm device member 14.

Connected with the cover casing 28 is a member having key hole slots 29 which may be extended over screws or the like 30 90 in the upright 11.

Spaced from the alarm device 14 at a suitable distance along the track is the alarm actuating mechanism which will now be described.

Spaced laterally from the rail 10 is an upright casing 20 shown in Figs. 1 and 3.

Extending through the wall of the casing 20 and also through the web of the rail 10 is a shaft 21 which is mounted for rotation. On the end of the shaft 21 in the casing 20 is mounted an arm 22, which normally extends substantially upwardly and has at its upper end a lateral extension 23. The chain 19^a is extended into the upper 105 part of the casing 20 and over a guide pulley 24 in said upper end, and is then secured to the extension 23, as illustrated in Fig. 3.

On the shaft 21 adjacent to the outer side 110

of one of the rails 10 is an upwardly extending trigger device or member 25 shown in Fig. 5, the upper edges of which are beveled as at 27. The parts are so arranged that 5 the chain 19 is held taut enough to permit the spring 18 to be normally extended, and yet so that the wheels of the train passing over the rail 10, when the train is moving in one direction, the trigger member 25 will 10 be struck and inclined in such a way as to impart limited rotation to the shaft 21, thereby moving the extension 23 downwardly and imposing tension on the spring 18. As soon as the wheel passes the trigger member 25, 15 the tension on the spring 18 will be released and the chain will jerk the head 16 toward the alarm device 14, thereby imparting a sharp blow to the ball 19, and causing it to be struck against the alarm device member 20 14.

In this connection it may be noted that the cylinders 14^a are preferably inclined slightly downwardly from their ends adjacent to the arms 12, so that the ball 19 25 will normally rest against the head 16.

We found by experiments that if the ball 19 is not used and the head 16 is caused to strike the alarm device member 14, the chain will tend to deaden the sound, whereas 30 the use of the steel ball 19 gives a clear ringing sound.

It will be noted that a train moving in another direction will not sound the alarm device, for the reason that when the member 35 22 is moved toward the right, for instance as is shown in Fig. 3, the chain 19 would not be pulled. It thus follows that the train which has passed the crossing where it is desired to give the warning will not actuate 40 our device for sounding an alarm.

When the train, however, is approaching the crossing the arm 22 is swung toward the left successively as each wheel of the train passes over the track, and engages the member 25, so that a continuous ringing is kept 5 up; the length of time of said ringing being determined by the length and speed of the train.

It will be noted that our device is so constructed and arranged that the working 0 parts are covered and protected from the weather, with the exception of certain parts which would not be injured or affected by 55 unfavorable weather conditions or snow or the like.

The parts are of simple construction; are inexpensive to make and the entire device is very durable.

It will be noted that it may be used for 60 wagon crossings, viaduct crossings, railroad crossings, and various signaling purposes.

Numerous changes may be made in the construction and arrangement of the parts 65 of our device without departing from the

essential features and purposes of our invention, and it is our intention to cover by our claims any modified forms of structure or use of mechanical equivalents, which may be reasonably included within their 70 scope.

We claim as our invention:

1. In a device of the class described, a support, a sounding device thereon, a cylinder having an open end adjacent to said sound device, a rod slidably mounted in said cylinder, a spring in said cylinder for normally holding said rod at one limit of its movement, a striking device interposed between said rod and said alarm device, said cylinder being inclined downwardly from its end adjacent to the alarm device, a rotatably mounted shaft, a trigger member thereon designed to be adjacent to a railroad track, an arm extending substantially 85 upward from said shaft, a lateral extension on said arm, a guide member, a flexible member secured to said rod and extended over said guide member and secured to said extension. 90

2. In a device of the class described, the combination of a rail with an upright member, a shaft rotatably mounted in said rail and said upright member, a trigger device on said shaft adjacent to said rail, an upwardly extending arm on said shaft adjacent to said upright, a lateral extension on said arm, a guide member on said upright, a second upright spaced from the first upright, an alarm device mounted 100 on said second upright, a cylinder mounted with its open end adjacent to said alarm device, and extending slightly downwardly therefrom, a spring mounted in said cylinder, a rod extended through said spring having a head on its end adjacent to said alarm device, a loose movable member in said cylinder between said head and said alarm device, and a flexible device secured to said extension and extended over said 105 guide and secured to said rod. 110

3. In a device of the class described, the combination of a rail, an upright member, a shaft rotatably mounted in said rail and upright member, a trigger device on said shaft adjacent to said rail, an arm on said shaft, a lateral extension on said arm, a guide member on said upright, a second upright, a pair of arms secured thereto and extending away therefrom in parallel relation, a metal sounding disk mounted between said last described arms, a shaft extended through said last arms and said second upright, spacer sleeves on said shaft between said disk and said last described arms, a cylinder mounted on one of said last described arms having its open end adjacent to said disk, a rod slidably mounted in said cylinder, a head on said rod, means for yieldingly holding said rod at one limit 120 125 130

of its movement, a ball between said rod and said disk, and a flexible device secured to said rod and extended over said guide device and operatively connected with said 5 arm.

4. In a device of the class described, an upright, a pair of arms secured thereto and extending laterally away therefrom, a sound disk mounted between said arms, a striking

device, means designed to be actuated by a 10 passing train for operating said striking device, and a casing detachably mounted on said upright for protecting said disk and spaced therefrom.

Des Moines, Iowa, October 9, 1918.

ZOUAVE S. RANDLEMAN.

CHARLES L. RANDLEMAN.
